Primary Examiner — Kimberly Barnes(74) *Attorney, Agent, or Firm* — King & Schickli, PLLC(57) **CLAIM**

The ornamental design for a visored helmet, as shown and described.

DESCRIPTION

FIG. 1 is an isometric view of a visored helmet according to our design;

FIG. 2 is a front view of the visored helmet of FIG. 1; FIG. 3 is a left side view of the visored helmet of FIG. 1, the right side view being a mirror image thereof; FIG. 4 is a top view of the visored helmet of FIG. 1; FIG. 5 is a rear view of the visored helmet of FIG. 1; and, FIG. 6 is a bottom view of the visored helmet of FIG. 1. The broken lines in the drawings depict portions of the visored helmet that form no part of the claimed design.

1 Claim, 6 Drawing Sheets(56)
